METHOD OF MAKING SPRING BEARD NEEDLES

Gustave Theodore Broberg, Torrington, Conn.,
assignor to The Torrington Company, Torrington, Conn., a corporation of Maine

Application March 16, 1939, Serial No. 262,250

1 Claim. (Cl. 163—5)

The invention relates to new and useful improvements in the method of making spring beard needles and the article produced thereby.

An object of the invention is to provide a method of making spring beard needles whereby the end of the beard is centered laterally over the groove therefor by pressure properly applied to the opposite sides of the head of the needle.

A further object of the invention is to provide a method of making spring beard needles whereby the stem of the needle adjacent the hook is stiffened by pressure applied to that portion of the stem so that the flexing of the needle when the beard is pressed during the knitting operation is confined substantially to a flexing of the beard.

A still further object of the invention is to provide a spring beard needle which is accurately dimensioned as to width of head, as viewed from the front or groove side, in the region of the hook and the portions of the beard and stem adjacent the hook for a given gauge of needle.

A still further object of the invention is to provide a spring beard needle wherein the flexing of the needle parts incident to the pressing of the beard is substantially confined to the beard portion.

These and other objects will in part be obvious and will in part be hereinafter more fully disclosed.

In the drawing which shows by way of illustration the various steps in the forming of a spring beard needle by my improved method, and also the improved needle produced thereby—

Figure 1 is a blank cut from a piece of wire from which the needle is to be formed;

Fig. 2 is a front view of the needle blank after the end portion thereof has been reduced and flattened in the region which is to form the beard, the hook and the supporting stem therefor, and after the end of the reduced portion has been shaped so as to provide a blunt end for the beard and the shank has been grooved;

Fig. 3 is a side view of the same;

Fig. 4 is a view similar to Fig. 3, but showing the blank bent to form the beard and hook, also the body of the blank flattened and the shank end bent to provide a supporting means for the needle;

Fig. 5 is a side view of the needle shown in Fig. 4;

Fig. 6 is an enlarged side view of the head of the needle after it has been subjected to pressure sufficiently to slightly flatten the side faces of the head;

Fig. 7 is a sectional view on the line 7—7 of Fig. 6;

Fig. 8 is a sectional view on the line 8—8 of Fig. 7, and

Fig. 9 is a sectional view on the line 9—9 of Fig. 6.

In the carrying out of the improved method, a wire is straightened and cut to proper lengths for producing a blank from which a needle is formed. Such a blank is shown in Fig. 1 and is indicated at 10. The blank is shaped so as to provide a reduced section 11 which is flattened on the face side of the needle as indicated at 12. It is also flattened on the side faces thereof. During this shaping of the needle, a tapered portion 13 is formed between the supporting shank and this reduced section 11. The end of the blank is shaped so as to provide a blunt nose 14 which is to be the end of the beard. The shank portion is grooved as indicated at 15. This shaping of the blank in the manner above described may be accomplished in any suitable way, such as by swaging, milling, stretching and the like. After the blank has been shaped as shown in Figures 2 and 3, then the side faces of the shank as viewed from the front or grooved end of the needle are flattened as indicated at 16 and the end of the shank is bent approximately at right angles as indicated at 17. This forms a supporting means for the needle. These flattened faces 16 gradually merge into the full circular dimensions of the blank in the regions of the groove so that the yarn loop will slide freely along the needle. All burrs or sharp edges formed during swaging or milling are also removed. The reduced portion 11 is bent back upon itself to form a hook 19 and the beard 20. The beard 20 is crimped at 21. The beard is spaced away from the supporting stem therefor, and the end 14 is normally spaced away from the groove formed in the shank. When the beard is pressed upon, the nose end 14 moves into the groove to allow the loop to pass over the same. The method steps followed up to this point in the making of the needle are the usual well-known steps in the forming of spring beard needles.

The needle with the beard, hook and groove formed therein as above described, is subjected to pressure at the side faces of the head of the needle to a sufficient degree so as to re-form the metal slightly. The pressure may be applied by hammering, squeezing, rolling, or in any other suitable way. This results in a flattened face 23 in the region of the hook, a flattened face 24 which extends substantially from the hook to a point

adjacent the groove 15, and a flattened face 25 along the beard which extends from the hook to a point approaching the crimped end thereof. This pressure is applied to both sides of the needle head as viewed from the front or grooved side of the needle. Several advantages are obtained by this re-forming pressure applied to the sides of the needle. When the blank is bent to form the beard, it often happens that the end of the beard is not centered laterally over the groove. As a result, the needles have to be very closely inspected, and the beard bent or shifted so as to properly center the same. This inspecting and positioning of the beard is usually performed after the hardening of the needle and is a manual operation. When, however, the needle head is subjected to pressure in the regions described above, the end of the beard will be centered laterally over the groove and will remain in such centered position, so that during testing after hardening, very little or no bending or shifting of the beard is necessary. Then again, this subjecting of the metal to pressure in the regions described stiffens and strengthens the stem between the hook and the groove so that the flexing of the needle when the beard is pressed, is confined substantially to a flexing of the beard and eliminates a large percentage of the backward motion of the head during this closing of the beard, in the knitting operation. Then again, this pressure applied to the side faces of the beard distributes the flexing strains incident to the closing of the beard so that it moves more rapidly to open position, which is of advantage in high speed machines. When the blank is bent to form the beard, the metal at the inner side of the hook indicated at 19a in Figures 5 and 6, bulges laterally slightly, due to the compressing of the metal at the inner side of the blank. When the head, however, is subjected to this pressure at the opposite sides thereof, the head of the hook is accurately dimensioned so that it may be of substantially uniform width in the region of the hook, and in adjacent

portions of the supporting stem and beard. This accurate and positive dimensioning of the needle head as to width after forming the beard is of special importance on finer gauge needles.

This pressing operation on the side faces of the needle head is performed after the shaping of the needle and the forming of the beard and prior to the hardening operation to which needles of this type are subjected. The extent to which the side faces of the head of the needle are flattened is relatively slight, but yet sufficient so as to accomplish an accurate dimensioning of the width of the needle and a change in the section modulus of the stem and beard so as to stiffen and strengthen the same in the manner described.

The method which has been described above produces a needle wherein the beard is centered laterally over the groove during the formation of the needle prior to the hardening of the same. It also produces a needle which is very accurately dimensioned as to width of the head, both when viewed from the front side or at right angles thereto. The advantages accomplished by this accurate dimensioning of the needle and the strengthening of the same in the regions stated are obvious and need not be described in detail.

Having thus described the invention, what I claim as new and desire to secure by Letters Patent is—

The method of making spring beard needles comprising shaping a blank so as to form a needle having a hook, a beard and a groove adapted to receive the end of the beard when pressed, and simultaneously applying pressure to the needle, after it is formed, at the opposite side faces of the hook, the beard and the stem between the hook and the groove, for reforming the metal therein sufficiently for accurately dimensioning the same as to width as viewed from the face on the grooved side thereof and so as to position and set the end of the beard laterally centrally over the groove.

GUSTAVE THEODORE BROBERG.

CERTIFICATE OF CORRECTION.

Patent No. 2,202,945.

June 4, 1940.

GUSTAVE THEODORE BROBERG.

It is hereby certified that error appears in the above numbered patent requiring correction as follows: In the heading to the drawing, name of inventor, for "G. T. BROBERD" read --G. T. BROBERG--; and that the said Letters Patent should be read with this correction therein that the same may conform to the record of the case in the Patent Office.

Signed and sealed this 30th day of July, A. D. 1940.
